UNITED STATES PATENT AND TRADEMARK OFFICE
Certificate

Patent No. D. 270,420

Patented September 6, 1983

Benjamin C. Baugh

Application having been made by Benjamin C. Baugh, the inventor named in the patent above identified, and The Coleman Co., Inc., the assignee, for the issuance of a certificate under the provisions of Title 35, Section 256, of the United States Code, adding the names of Dennis Y. Hefling and Frank T. Schmidt as joint inventors, and a showing and proof of facts satisfying the requirements of the said section having been submitted, it is this 17th day of July, 1984, certified that the names of the said Dennis Y. Hefling and Frank T. Schmidt are hereby added to the said patent as joint inventors with the said Benjamin C. Baugh.

Fred W. Sherling,
Associate Solicitor.
